UNITED STATES PATENT OFFICE.

RALPH A. JORDAN AND NICHOLAS S. FILLYA, OF NEW YORK, N. Y.

FORM FOR PLASTIC MATERIALS.

Application filed November 8, 1926. Serial No. 146,903.

This application relates to a new and improved form for making walls of concrete and other plastic materials.

One of the objects of our invention is to provide a form made of metal members which can be used any number of times and which can be readily assembled and dismantled.

Another object of our invention is to provide a knock-down form, the individual members of which will be held very rigidly.

Another object of our invention is to provide a form which shall be adjustable so as to enable it to be used for making walls and wall sections of different contours.

Other objects of our invention will be set forth in the following description and drawings which illustrate a preferred embodiment thereof, it being understood that the above general statement of the objects of our invention is intended to generally explain the same and not to limit it in any manner.

Fig. 1 is a top view illustrating an assembled form.

Fig. 2 is a detail elevation, this view being taken along the line 2—2 of Fig. 1.

Fig. 3 is a sectional view partially in elevation taken along the line 3—3 of Fig. 1.

Fig. 4 is a detail view partially in section showing one of the upright panel members and accompanying parts.

Fig. 5 is a section on the line 5—5 of Fig. 4.

Fig. 6 is a plan view illustrating how two superposed channel members can be connected to increase the height of the form.

Fig. 7 is a section along the line 7—7 of Fig. 6.

Fig. 8 is a detail view showing one of the wedge members.

Fig. 9 is a bottom view of the device shown in Fig. 8.

Fig. 10 is a front elevation showing how a platform member can be connected to a channel.

Fig. 11 is a section along the line 11—11 of Fig. 10.

Fig. 12 is an elevation showing a device for holding a panel firmly in position.

Fig. 13 is a top view of the device shown in Fig. 12.

Fig. 14 is a sectional view showing how opposite channel members are connected to each other.

Fig. 15 is a sectional view illustrating the concrete wall made with the use of the form illustrated herein.

Fig. 16 is a detail view showing how walls having obtuse angles can be formed.

The device comprises a group of four longitudinal rails, the respective members of which are connected to the members of a group of four transverse rails. As shown in Figs. 1 and 2, the left hand longitudinal rails comprise an upper rail or angle iron 10' and a lower rail 10². The right hand longitudinal rails comprise a bottom member 25' and a top member 25. The transverse rails comprise two front rails 11 and two rear rails 10.

The left hand longitudinal rails 10' and 10² are directly connected to the rear transverse rails 10 by means of suitable detachable fastening members F. The right hand longitudinal rails 25 and 25' are connected to the front transverse rails 11 by means of intermediate coupling members, each of which consists of two angle irons. For example, and as shown in Fig. 1, the top rail 25 is connected to a lower rail 24 by means of clamp bolts 23 which pass through slots 26 and 27 in the lower rail member 24. As clearly shown in Figs. 1 and 3, the top rail member 11 is connected to a rail member 20 located directly beneath it, by means of similar bolts 23 which pass through slots 21 and 22 of the rail member 20. Similar intermediate connections are provided between the rails 25' and the lower rail 11. The rails 20 and 24 are connected to each other by detachable fastenings F' and the rails project beyond F' and abut the faces of an upright angle iron 13 which forms the inner corner member of the form. It is not necessary to provide any fastening means between the member 13 and the upper and lower pair of rails 24 and 20 because the configuration of the parts provides the necessary firm frictional fit. The inner corner member 13 is associated with an outer corner member 12 also made of angle iron and the rolled end flanges of the member 12 abut the adjacent outer rails. The end flanges of the outer corner member 12 have lugs L connected thereto and these lugs are provided with bolts B which extend through notches in the adjacent rails which are held in clamped position by means of nuts N. By shifting the rails 24 and 20 with respect to their adja-

105

cent and connected rails, it is obvious that the position of the inner corner member 13 can be varied when the spacing between the rails is varied, so that the device can be used for forming walls of varying thickness. The horizontal rails before mentioned are connected to upright channel irons 16 by means of fastening devices shown clearly in Figs. 4 and 5. The parallel webs of the upright channel irons 16 are provided with inner U-shaped bars 17 having sleeves 18 provided with pivot members 18² by means of which bars 17 are pivotally connected to said uprights 16. The sleeves 18 are provided with bolts 18³ which project through slots in the horizontal rails so that the uprights 16 can be clamped to the rails by means of wing-nuts 18'. The uprights can be clamped to their rails by means of ordinary nuts N² instead of wing-nuts 18' shown in Figs. 4 and 5.

The uprights 16 are held in spaced position by means of intermediate sleeves 34 and end sleeves 35 which are externally tapered. Bolts 36 extend through the members 34 and 35 as shown in Fig. 14 and nuts N² are provided for firmly clamping the uprights 16 together.

The spaces between the uprights 16 are filled by means of upper panels 28 and lower panels 29. These panels 28 and 29 are provided with external strengthening corrugations 14 which are secured thereto by means of rivets 30. As shown in Fig. 1 the ends of the panels fit between the internal flanges of the uprights.

The parallel webs of the uprights 16 are provided with perforations 32' in which pins 32 are fitted. Forked members 31 are provided with bases 31² which can fit slidably upon the webs of the upright channel irons 16. The forked ends of each said fastening member are adapted to engage one of the said pins 32 as shown in Fig. 3; for example, and these forked ends are wedge shaped so that upon forcing each member 31 into position it firmly holds one of the panels in position. The wedging members 31 are held in the position shown in Fig. 3, by friction. In order to securely lock the panels into position, it is preferable that the members 31 should be inclined when they are in the locking position and hence the bases 31² of the members 31 are provided with screws 33. These screws have wing-shaped ends so that they can be adjusted with respect to the bases 31² and the adjustment of these screws regulates the inclined position of the respective members 31.

In order to more securely hold each panel in position, the device shown in Figs. 12 and 13 can be provided. This consists of a member 47 having chain members 45 which can be caused to engage the openings 32' in adjacent uprights 16. A bolt member 46 can

be adjusted with respect to the member 47 so that each panel is forced against the adjacent uprights 16 with great force.

Platform members 42 can be caused to engage horizontal pins 43 passing through openings in the channels 16 and a platform 44 can be formed upon the platform members 42. As clearly shown in Fig. 11 the bottom of each platform member 42 abuts the intermediate face of the respective upright 16 and each platform member 42 fits snugly between the webs of its respective upright 16 so as to securely hold the platform members in position.

In order to raise the height of the device, additional channel members may be connected to the bottom channel members as shown in Figs. 6 and 7. As shown in Figs. 6 and 7 adjacent superposed uprights 16 and 16² are provided with an intermediate U-shaped connecting member 37 which fits snugly between the flanges of said uprights 16 and 16². A bent and resilient member 39 fits between the flanges of the inner connecting member 37, and pins 41 which pass through openings 32' in channels 16 and 16², and through slots 38 in members 37, limit the outward movement of members 39. Member 39 is provided with threaded members 40 which tend to force member 39 outwardly when said threaded members 40 are turned, so as to clamp the members in the position shown in Fig. 7.

In the embodiment shown in Fig. 16 one of the corner channel members such as the member 12, is formed of two separate plates 12' and 12² connected together by hinge members 15. This construction enables walls having obtuse or other angles to be formed, in addition to the construction shown in Fig. 1 which enables walls having right angles to be formed.

The use of both of the inner rails and the outer rails is not necessary in all cases. For example, if an excavation has been made for a foundation, the wall of the excavation can replace the outer rails so that only a single set of inner rails need be employed in such circumstances. When the form has been set up, concrete or other plastic material is poured in between the panels and after the wall has set everything can be removed except the sleeves intermediate the upright channels, as shown in Fig. 15.

We have shown a preferred embodiment of our invention, but it is clear that numerous changes and omissions could be made without departing from its spirit.

We claim:-

1. A form for plastic materials comprising horizontal members having openings formed therein, vertical members having screws pivotally connected thereto, the said screws being adapted to pass through the openings in

the horizontal members, and clamping means mounted upon the said screws and adapted to engage the horizontal members.

2. A form for plastic materials comprising connected horizontal members and vertical members adapted to form a framework, lateral panels located between the said vertical members and abutting lateral extensions of the said framework, the said vertical members having pins connected thereto and slideable wedging members adapted to engage the said pins and the said panels to hold the said panels in position, the said wedging members being inclined in a direction transverse to said panels.

3. A form for plastic materials comprising connected horizontal members and vertical members adapted to form a framework, panels located between the said vertical members, the said vertical members having pins connected thereto, slideable wedging members adapted to engage the said pins and the said panels to hold the said panels in position, said slideable wedging members having movable pins connected thereto and adapted to abut the said upright members so as to regulate their inclination.

4. A form for plastic materials comprising a framework of connected horizontal members and upright members, panels adapted to close the spaces between the said upright members so as to close the said framework, a rigid member connected by flexible means to a pair of adjacent upright members, and a movable member connected to the said rigid member and adapted to force a panel against the uprights associated therewith.

5. A form for plastic materials comprising a pair of connected horizontal members having their ends projecting beyond their point of connection, and an upright associated with the ends of the said horizontal members, the said upright having faces against which the projecting ends of the said horizontal members are adapted to abut so as to hold the said upright in position.

6. A form for plastic materials comprising an angular upright corner member having the portions thereof hingedly connected to each other, horizontal rails turnably connected to each other and respectively associated with the respective portions of the said corner member, and clamping means adapted to connect each rail to the corresponding portion of the said corner member.

7. A form for plastic materials comprising a plurality of upright and substantially U-shaped channel members, each said channel member having a base portion and forwardly projecting wings, panels located intermediate said channel members and serving to space the said channel member pins passing laterally through the forwardly projecting wings of the said channel members, and slideable wedging means adapted to be mounted upon the wings of the said channel members and to pass between the said pins and the said panels to wedge the said panels in position by forcing said panels against said wings, said wedging members being inclined transversely to said panels.

In testimony whereof we affix our signatures.
